UNITED STATES PATENT OFFICE

GUSTAV ADOLF SCHETTLER, OF LEEDS, ENGLAND, ASSIGNEE TO THE TURNER TANNING MACHINERY COMPANY, OF PORTLAND, MAINE, A CORPORATION OF MAINE

LEATHER-WORKING MACHINE

Application filed January 19, 1928, Serial No. 247,877, and in Great Britain January 27, 1927.

This invention relates to machines for operating upon hides, skins, leather and other similar pieces of work and is illustrated as embodied in a machine for setting and rolling heavy leather. It is to be understood, however, that the invention and various important features thereof may have other uses and applications.

As heretofore commonly constructed, setting machines have been provided with a bed roll for presenting pieces of work in succession to a bladed cylinder and with a feed roll arranged for co-operation with the bed roll in feeding the work past the cylinder, the construction and arrangement being such that yielding of the bed roll with respect to the cylinder in accommodating thicker portions of the work resulted in lessening of the grip upon the work of the co-operating feed and bed rolls so that at the very time the feeding should be most effective there was a distinct tendency to reduce the efficiency of the feeding means. While several attempts have been made to overcome this condition none of the proposed constructions has gone into commercial use to any substantial extent.

It is an object of the invention to provide an improved construction for leather working machines which, while correcting the deficiency pointed out above, will at the same time retain all of the best features of the commercial forms of setting machines. It is a further object of the invention to provide a machine which will be simple and durable in construction and highly efficient for the purposes intended.

To these ends, and in accordance with an important feature of the invention, means is provided for mounting the feed roll for bodily movement about a plurality of axes so that it may yield with respect to the bed roll to accommodate variations in thickness of the piece of work being fed by the two rolls and so that both rolls may move together when the bed roll adjusts itself with respect to the work treating member in accommodating variations in the thickness of the work being operated upon. By this construction and arrangement the feed roll maintains an efficient gripping contact with the work at

all times irrespective of the position of the bed roll with respect to the work treating member. Conveniently, the feed roll is mounted upon pivoted members which yield away from the bed roll to permit the roll to adjust itself to work passing over the bed roll, and the latter is also connected to the said members for yielding movement so that both feed roll and bed roll may yield together relatively to the work treating member. Preferably too, and as illustrated, the bed roll is operated by a toggle so arranged that when in straightened position the centers of the toggle and of its lower pivotal mounting are in line with the centers of the bed roll and feed roll, thus providing a construction effective for relatively heavy rolling of the leather between the feed roll and the bed roll.

For securing a relatively broad support for the work while it is being operated upon, the illustrated machine is provided with a work support of improved construction upon which a piece of work is supported in conjunction with the bed roll, the work support being pivotally mounted upon the shaft of the bed roll so as to move independently of the bed roll while pressing the work yieldingly against the work treating member, which preferably and as shown, is a bladed cylinder. As shown, the work support is a presser attachment comprising a number of presser members individually yieldable and having contacting surfaces angularly arranged with respect to the direction of feed of the work so as to obviate any tendency to marking of the work, as might occur if the lines between the presser members were arranged at right angles to the longitudinal dimension of the presser attachment. Conveniently means is provided for instantaneously adjusting the pressure of the work support with respect to the working cylinder, said means comprising also means for readily securing the work support in adjusted position.

In setting operations upon certain kinds and classes of work, it is desirable to apply a liquid to the surface of the piece of work to condition it for the operation of the work treating means. Accordingly, means is provided for spraying liquid upon the piece of

work passing over the bed roll, the spraying means being arranged to become operative when the bed roll moves into position to present the work to the work treating means and to become inoperative when the bed roll moves away from the work treating means toward a work receiving position. Conveniently the controlling means for the spraying means comprises a valve in a supply pipe arranged to be operated by a tappet mounted on a part which moves with the bed roll. As illustrated, this moving part is the upper toggle of the toggle mechanism provided for moving the bed roll between work receiving and work presenting positions.

In accordance with a further feature of the invention, the illustrated machine is also provided with treadle mechanism so constructed and arranged as to reduce to a minimum the transmission of vibration and movement of moving parts of the machine to the treadle, so that the work of the operator is facilitated by easier and smoother operation of the treadle. For this purpose the illustrated treadle is arranged to be returned to its initial position by a combined dash pot and spring mechanism which cushions what would otherwise be a considerable reaction upon the treadle of the parts which normally operate automatically to return moving parts of the machine to a position of rest.

These and other features of the invention and novel combinations of parts will now be described in detail in the specification and then pointed out more particularly in the appended claims.

In the drawings,

Fig. 8 is an end elevation of the improved form of gearing;

Fig. 9 is an end elevation of a spraying apparatus with which the machine is equipped, and

Fig. 10 shows details of the treadle mechanism for the illustrated machine.

Figs. 1, 2 and 3 are drawn to a smaller scale, and Figs. 4 to 8 to a larger scale than Fig. 9.

The illustrated setting and rolling machine comprises rigid side frames 1, 1, each of which

has a pair of bell crank levers 2, fulcrumed thereon at 3. At one end each pair of levers (Fig. 2) has pivotally connected thereto one end of a beam 4, the point of connection 5 being above the fulcrum of the bell crank levers. The levers 2 of each pair are disposed on opposite sides of the corresponding side frame and have the pivoted beams located between them in order to obtain rigidity sideways of the structure. Each of the beams 4 extends rearwardly and at its rear end is supported by means of a vertical rod 6 which passes through it and rests on the side frame 1. Conveniently, a compression or volute spring 7 is interposed between a self-aligning plate or washer 8 which presses upon the beam and lock nuts 9 on the upper end of vertical rod 6. Nuts 10 are provided on the rod 6 below the said beam to take the downward thrust of the spring. At its lower end the rod passes through a boss 11 on the side frame and is secured against upward movement by means of nuts 12, a self-adjusting washer 13 being interposed between the under side of the boss and the nuts. An opening 14 is provided in the side frame below the boss to accommodate the said nuts and washers, and it is at the bottom of this opening that the rod 6 contacts with and rests upon said frame 1. The rods 6 pass through clearance holes or slots (not shown) in the beams 4 and bosses 11 respectively so as to permit the beams to yield as will be described subsequently herein.

The aforesaid bell crank levers 2 are also spring controlled from below and to this end are pivotally connected to eye bolts 15 (Figs. 1 and 2) extending downwards through lugs 16 on the corresponding side frames with compression springs 17 interposed between the upper side of said lugs and washers 18 backed by nuts 19 higher up on the bolts. The bolts 15 are passed through clearance holes or slots (not shown) in the lugs and are secured against upward movement by nuts 20 on the lower end thereof with self aligning washers 21 interposed between the nuts and the opposing faces of the lugs.

The pivoted beams 4 carry a hollow feed or presser roll 22, (Figs. 1, 2 and 3) each trunnion 23 of which is mounted in a bearing located centrally on the corresponding beam 4, i. e. approximately midway between the opposite ends thereof. This roll co-operates with a hollow bed roll 24 which in its working position is disposed below the feed roll 22. The bed roll has each trunnion 25 thereof mounted in bearings in swing arms 26 (Fig. 1) which are fulcrumed at 27 upon the aforesaid beams 4. These swing arms are also arranged in pairs, there being one pair to each beam, the arms in each pair being disposed on opposite sides of the beam 4 to provide rigidity. The fulcrums of the swing arms are located adjacent to the front ends of

the beams, i. e. near the pivotal connections between the beams and the bell crank levers, so that when the bed roll 24 is in the working position, the arms are inclined downwards. The bed roll is swung to and from the working position by means of toggle links 28, 29, pivotally connected to the bed roll trunnions 25 at one end and extending downwards and pivotally connected to the corresponding side frames at the other end upon bearings 30. The upper link 28 of each toggle is located between the corresponding pair of swing arms 26 and the lower link 29 is bifurcated to fit over the bearing 30 therefor in the lower part of the corresponding side frame. At this point adjustable shoes 31 are provided on opposite sides of the side frame 1 to receive the bifurcated end of the toggle link 29 so as to provide maximum distribution of the pressure when the toggle is straightened. A further feature of construction is that the toggle joint (Figs. 1 and 9) is formed by a pin 32 in one link working in a corresponding socket 33 in the other link, the pin and socket 25 being in contact throughout the full length thereof. The arrangement is such that, when the toggles are straightened on the centers thereof by operation of the pitman 33a, the centers of the feed or presser roll 22 and of 30 the bed roll 24 and also the centers of the toggles 28, 29 and of the bearing 30 are all located in one and the same straight line, i. e., a, b in Fig. 1. As shown, the pitman 33a holds the toggle link 29 with the center of the pin 32 fixedly in one position while the machine is operating on a piece of work. But the toggle link 28 may move to the right, in Figs. 1 and 9, to permit the bed roll to adjust itself yieldingly to the thickness of the work 35 between it and the bladed cylinder 34. In Fig. 9, the spaced shoulders 28a and 29a, respectively on the toggle links 28 and 29, indicate the extent of the movement of the link 28 to permit the described adjusting movement 40 of the bed roll 24.

For operating upon the work there is provided a bladed working cylinder or tool 34 adapted to perform setting and rolling operations on leather and with which the aforesaid 45 rolls co-operate. The cylinder 34 is disposed at the rear of the machine, i. e. behind the bed roll 24, and at each end is mounted in a bearing (Fig. 1) formed as a slide 35 adapted for movement horizontally on a corresponding guide 36 on the side frame 1 so as to permit of adjustment of the cylinder in relation to the bed roll, or its removal or replacement. Conveniently each slide 35 is engaged by a screw 37 rotated, as shown, by worm gearing 50 from a common shaft 39 rotated in its turn through mitre gears (not shown) from a shaft 40 (Fig. 2) operated by a hand wheel 41 at the front of the machine.

By mounting the bed roll 24 and the feed roll 22 upon spring loaded beams 4 pivotally

connected to yieldable bell crank levers 2 and providing a pivotal mounting of the bed roll 24 about the center of the pin 32, the rolls 22, 24 while being capable of subjecting the work passed between them to heavy pressure, as in setting and rolling operations, are enabled also to yield together relatively to the working tool 34, if necessary, to accommodate variations in the thickness of the material. During the simultaneous yielding of the rolls 22, 24, away from the tool 34, the beams 4 turn the bell crank levers 2 about their fulcrums against the action of the compression springs 17 associated with said levers. Further, the feed roll 22 can, if necessary, yield relatively 70 to the bed roll 24 by the beams 4 turning about their points of connection with the bell crank levers 2, against the action of the volute or compression springs 7 on the rear ends of the beams. Another advantage of the construction shown resides in the fact that the movement of the bed roll 24 to and from its working position requires a comparatively small amount of effort, despite the heavy pressure between the rolls 22, 24, owing to the fact that it is suspended from a point above it so that its weight is practically removed from the toggles when in their open position.

Fulcrumed on the bed roll trunnions 25 on the inside of the swing arms 26 are levers 42 which at their rear ends carry a work support in the form of a presser attachment comprising a housing 43 (see particularly Figs. 3 to 6 and 9) provided with a longitudinal opening 44 therein for the reception of a number of separate presser members 45 arranged side by side in contact with each other and each backed by a compression spring 46. Conveniently, as shown in Fig. 5, the longitudinal edges of the opening are undercut to form abutments 47 and the presser members 45 are formed with shoulders 48 for engagement with the abutments to limit the outward movement of the presser members under the action of the springs 46. The compression springs 46 are individually adjustable to vary the pressure thereof in accordance with requirements, and to this end contact with washers or plates 49 associated with screws 50 (Figs. 4 and 5) threaded through a web or wall 51 in the housing and locked in position after adjustment by lock nuts 52. The outer ends of the levers 42 are pivoted at 53 (Figs. 1 to 3) to plates 54 which are slidable on rods 55 fixed in and depending from collars 56 freely mounted on eccentrics 57 (Fig. 3) on a horizontal shaft 58 carried at its opposite ends in bearings on the pivoted beams 4. Compression springs 59 are interposed between said plates 54 and other plates 60 fixed 100 higher up on the rods 55 whereby the work support, comprising the housing 43 and the presser members 45 therein, is pressed yieldingly toward the bladed cylinder. The pressure exerted by these springs 59 may be va- 105 110 115 120 125 130

ried by rotating the eccentric shaft 58 for which purpose the latter has a handle 61 (Fig. 1) fixed on one end thereof. A slotted segment 62 is fixed on the pivoted beam adjacent to the handle, to which the latter may be clamped in adjusted position by nut and bolt or equivalent means 63. In order to obviate the formation of lines on the back of the leather the joints 64, Figs. 4 and 6, between the presser members 45 are formed at an angle to the direction of movement of the leather (Fig. 6). As represented in Figs. 3 and 9, the work support bends the work 65, i. e. the leather, in one direction and the bed roll 24 bends the leather in the opposite direction, this arrangement resulting in the bottom fibres of the leather being stretched to the same extent as the grain fibres. The work support is preferably angularly adjustable relatively to the working cylinder and for this purpose may be furnished with a trunnion 66 at each end which fits freely in the corresponding lever 42. The housing is fixed at each end after adjustment by means of a screw 67, (Fig. 3) inserted through a slot 68 in a web integral with the housing 43 and into the corresponding lever 42. A transverse screw 69 (Figs. 4 and 6) at each end of the housing prevents endwise movement of the pads therein.

The feed roll 22 is positively and continuously driven by a chain 70 and sprocket wheels 71, 72, (see Fig. 2) independently of the machine drive clutch mechanism, represented generally at 73, which latter controls the operation of the toggles 28, 29 for moving the bed roll 24. The bed roll is driven by mangle gears 74, 75, (Figs. 1 and 2) from the feed roll 22 and the speed of these rolls may be changed for the various operations which the machine is to perform by substituting other chain wheels for those at 71, 72 for driving the feed roll.

To facilitate engagement between the mangle gears 74, 75 on the feed roll and bed roll and to obviate breakage of the teeth when the bed roll is brought from the open position into working position, the invention includes as one of its features an improved construction of gearing. To this end, as illustrated in Figs. 7 and 8, the gear wheel 75 is capable of a limited turning movement upon a sleeve or bushing 76 keyed to the trunnion 23 of the feed roller 22. A driving connection between the sleeve 76 and wheel 75 is provided by dog clutch teeth 77 and 78 respectively on parts 76 and 75 which provide lost motion between the two in a rotary direction. That is to say, recesses 79 between the teeth 78 are wider than the teeth 77. By means of one or more springs the wheel 75 is yieldingly held in a normal position on the sleeve or bushing 76 from which position it is capable of moving slightly in either direction before transmitting the drive in positive manner to the

bushing. For example, springs 80 on a rod 81 fixed in lugs 82 on the sleeve 76 act on opposite sides of a lug 83 on the gear wheel 75. The rod 81 passes through a clearance hole in the lug 83 to allow for yielding movement of the wheel in either direction. In the machine shown in Figs. 1 and 2, only the gear wheel 75 is constructed as aforesaid, it being obvious, however, that both wheels 74 and 75 may be constructed in the manner described in connection with wheel 75. When the mangle gears engage, upon the bed roll being moved to operative position, the toothed wheel 75 can yield if necessary owing to the limited backlash provided, and upon transmission of drive from one to the other, the connecting clutch teeth 77, 78 between the wheel 75 and the sleeve 76 provide a positive drive as soon as the lost motion or backlash has been absorbed. To facilitate easy meshing of the gear teeth, each wheel 74, 75 may comprise a plurality of sections, e. g., as illustrated in Fig. 7, arranged side by side with their teeth staggered, as shown in Fig. 8, the sections being clutched together by interchanging dog clutch teeth 84, 85, or otherwise positively connected. When each wheel is designed to yield, the sections thereof are held in position on the sleeve 76 by a flange at one end of the sleeve and a collar 86 fixed on the other end. It will be understood that in the case of a wheel, e. g., 74, which does not yield the sections thereof may be similarly mounted on a sleeve without the spring arrangement.

The toggles 28, 29 aforesaid may be actuated from a crank shaft 87 (Figs. 1 and 2) driven by suitable mechanism which includes the clutch mechanism 73 and means of known form (and therefore not requiring detailed description) for automatically throwing the clutch out of action at each half revolution of the crank shaft, thus bringing the machine to rest with the bed roll in the operative and inoperative positions alternately. As represented generally in Figs. 1 and 2, such automatic means include a half cycle cam 88 on a gear 89 and a co-operating lever 90 connected by a spring controlled link 91 with a clutch fork 92 and associated with a starting treadle 93. For a more detailed description of the mechanism for moving the bed roll 24 from work receiving to work presenting position and in the reverse direction and for maintaining it in work receiving position and subsequently in work presenting position during the operation of the bladed tool, reference may be had to United States Letters Patent No. 873,790, granted Dec. 17, 1907, upon application of John Rood and Franklin J. Perkins.

For operating the clutch to set the machine in motion, the invention provides an improved treadle arrangement wherein a starting treadle 93 is freely mounted on its shaft

94 so that after depression for starting purposes it can return to normal position independently of the shaft. As shown, the treadle 93, when depressed, turns the shaft 94 by contact with an arm 94a fast with the shaft. The treadle is free to turn in an upward direction on and independently of the shaft and has combined with it a spring 94b carried by a rod 94c which works in a stationary cylindrical housing 95 and is fitted with a piston 96 for air control which acts against a projection 97 on the treadle to lift the latter. The outward movement of the spring and piston are limited by adjusting nuts 97a on the rod 94c which engage one end of the housing on the outside. This arrangement prevents jar on the treadle when the automatic means come into operation to throw the clutch out of action. The effect of the spring and air cylinder device 96 is that the treadle is raised to normal position by a gentle motion immediately it is released by the operator.

The illustrated machine is also provided with a spraying apparatus situated so as to act upon the skin at the desired points. As illustrated in Fig. 9, the spraying apparatus comprises a perforated pipe 98 disposed in the space between the working cylinder 34 and the feed and bed rolls 22, 24, and connected by a pipe system 99 with a pump or other means (not shown) whereby oil, water or suitable liquid can be sprayed in the desired direction, e. g. downwards on to the leather passing between the bed roller and the cylinder. The pipe system includes a piston or plunger valve 100 which is normally closed by spring action. The valve is disposed opposite one of the toggle links 28 which latter is fitted with an adjustable tappet 101 for action on a valve piston or plunger 102. Thus the machine, when carrying out the combined operations of dampening, setting the grain, and rolling, operates in the following manner. The piece of work, which may be a hide, skin or piece of leather, having been placed over the bed roll 24 is carried forward into contact with the bladed cylinder 34 when the treadle is depressed, and this motion by reason of the action of the tappet 101 opens the valve 100 and puts the spraying apparatus into action. The rotary motion of the bladed cylinder distributes the liquid evenly over the surface of the piece of work, the said liquid acting as a lubricant between the setting tool and the grain of the piece of work whereby a very fine and close grain is obtained. After any given portion of the work has been thus dampened and set, it passes on between the presser and bed rolls 22, 24 and is thereby subjected to heavy pressure which constitutes what is known as the "first rolling operation". It will therefore be seen that during one passage through the machine the work may be subjected to three

different operations which are performed in a continuous manner. In other words, the method comprising the said steps of dampening, setting and rolling can, by the machine herein-described, be carried out in one operation or at one handling of the work. The surplus oil or other liquid may be collected in a suitable receptacle for repeated use.

For the operation of striking out (i. e. removing moisture), the feed and presser roll 22 is covered with a felt sleeve for absorbing moisture from the pieces of work while the tool or cylinder 34 is operating on the work against the bed roll 24. For sammying, (i. e. dampening) both the bed roll 24 and presser roll 22 are covered with loose fitting felt sleeves, the work cylinder being spaced away from the bed roll 24 in a position to press the work against the presser members 45. In the latter case the action of the working cylinder 34 is confined to spreading the skin in cooperation with the presser members 45. For setting operations, the presser roll 22 is either a smooth metal roll covered with a non-corrosive metal such as brass or copper, or it is covered with a hard rubber vulcanite; and the bed roller is rubber covered and has a yielding surface.

In using the machine, a piece of work is placed over the bed roll 24 and the presser members 45 while these occupy the open or inoperative position represented by dot and dash lines in Fig. 3, approximately one-half of the piece of work being introduced at any time. The machine is then started and the toggles are actuated to move the bed roll so that the work is carried into contact with the bladed cylinder 34 and also with the feed and presser roll 22, whereupon the skin is drawn past the working cylinder in the rotation of the two rolls 22, 24. After one portion of a piece of work has been operated on, the treadle is operated to cause the bed roll 24 to move to open or work receiving position, so that the untreated portion of the work may be thrown over bed roll 24 and the work supporting presser members 45. A second depression of the treadle causes the bed roll and presser members to move toward the bladed cylinder 34 to press the work thereagainst, the feed roll 22 being engaged with the work first to insure clamping thereof on the bed roll before the cylinder starts operating on the work.

Having thus described my invention, what I claim as new and desire to secure by Letters Patent of the United States is:

1. In a machine for operating upon hides, skins, leather, and other similar pieces of work, means for treating a piece of work, a support for presenting the piece of work to the work treating means, said support being movably mounted, means for yieldingly pressing the support toward the work treating means, and a feed roll for co-operation with

the support in feeding the work mounted to move about a plurality of axes to permit movement of the feed roll with respect to the support and yielding of both feed roll and support with respect to the work treating means.

2. In a machine for operating upon hides, skins, leather, and other similar pieces of work, a work treating member, a support for presenting the piece of work to the work treating member, said support being movably mounted, means for yieldingly pressing the support toward the work treating member, a feed roll for co-operation with the support in feeding the work, and a mounting for the feed roll pivoted for movement away from the support to permit adjustment of the feed roll with respect to the support, said mounting being movable also in another direction to permit movement of the feed roll together with the support in directions toward and from the work treating member.

3. In a machine for operating upon hides, skins, leather, and other similar pieces of work, a rotary cylinder for treating a piece of work, a bed roll for presenting the piece of work to the rotary cylinder, said bed roll being movably mounted, means for yieldingly pressing the bed roll toward the rotary cylinder, and a feed roll for co-operation with the bed roll in feeding the work mounted to move about a plurality of axes to permit movement of the feed roll with respect to the bed roll and yielding of both rolls with respect to the rotary cylinder.

4. In a machine for operating upon hides, skins, leather, and other similar pieces of work, a rotary cylinder for treating a piece of work, a bed roll for presenting the piece of work to the treating cylinder, means for pressing the bed roll yieldingly toward the work treating cylinder, a feed roll arranged for co-operation with the bed roll in feeding the work past the work treating cylinder, and members for supporting the feed roll arranged to yield in two directions so that the feed roll may be self adjusting with respect to the bed roll and also self adjusting together with the bed roll with respect to the work treating cylinder.

5. In a machine for operating upon hides, skins, leather, and other similar pieces of work, a rotary cylinder for treating a piece of work, a bed roll for supporting and backing a piece of work during the operation of the work treating cylinder, a feed roll for co-operation with the bed roll in feeding the work past the work treating cylinder, and means for supporting the feed roll and the bed roll each for movement about a plurality of axes so that the feed roll may yield relatively to the bed roll and both the feed roll and bed roll yield together relatively to the work treating cylinder, and so the bed roll may

move bodily between work receiving and work presenting positions.

6. In a machine for operating upon hides, skins, leather and other similar pieces of work, a rotary cylinder for treating the work, a bed roll for presenting a piece of work to the cylinder, a feed roll for co-operation with the bed roll in feeding the work, means for supporting the feed roll and the bed roll, and a toggle for moving the bed roll between work receiving and work presenting positions with respect to the work treating cylinder, the construction and arrangement being such that the centers of the toggle and of its pivotal mountings are in line with the centers of the feed and bed rolls in the work presenting position of the bed roll.

7. In a machine for operating upon hides, skins, leather and other similar pieces of work, a work treating cylinder, a bed roll for presenting a piece of work to the cylinder, a feed roll for co-operation with the bed roll in feeding the work past the work treating cylinder, and means for mounting the feed roll for pivotal movement about an axis above the bed roll so that it may adjust itself upwardly and downwardly with respect to the bed roll and for pivotal movement about another axis to move with the bed roll in adjusting movements of the latter with respect to the work treating cylinder.

8. In a machine for operating upon hides, skins, leather and other similar pieces of work, a work treating cylinder, a bed roll for presenting a piece of work to the cylinder, a feed roll for co-operation with the bed roll in feeding the work past the work treating cylinder, pivoted members for supporting the feed roll, and swing arms for pivotally connecting the bed roll to the pivoted members, said pivoted members being mounted to yield about one axis during relative movement between the feed roll and the bed roll and also to yield about a second axis during combined movement of the feed roll and bed roll with respect to the work treating cylinder.

9. In a machine for operating upon hides, skins, leather and other similar pieces of work, a work treating cylinder, a bed roll for presenting a piece of work to the cylinder, a feed roll for co-operation with the bed roll in feeding the work past the work treating cylinder, pivoted members for supporting the feed roll, pivoted spring controlled members for yieldingly supporting the pivoted members, and swing arms for connecting the bed roll to the pivoted members, the pivoted members yielding about their pivotal connection with the spring-controlled members during adjusting movement between the feed roll and the bed roll, said pivoted members being movable also about the pivotal mounting of the spring-controlled pivoted members during movement of the bed roll and feed roll relative to the work treating cylinder.

10. In a machine for operating upon hides, skins, leather and other similar pieces of work, a bladed member, a bed roll movable between work receiving and work presenting positions for presenting a piece of work to the bladed member, a feed roll for co-operation with the bed roll in feeding the work past the bladed member, pivoted members for supporting the feed roll, pivoted bell crank members for supporting the first-mentioned pivoted members, and arms for pivotally connecting the bed roll to the first-mentioned pivoted members, said first-mentioned pivoted members being movable about their pivotal connections with the bell crank levers to permit the feed roll to adjust itself with respect to the bed roll, said first-mentioned pivoted members also movable about the pivots of the bell crank levers to permit movement of the feed roll and bed roll in directions toward and from the bladed member. 70
15. In a machine for operating upon hides, skins, leather and other similar pieces of work, a bladed member, a bed roll for presenting a piece of work to the bladed member, a feed roll for co-operation with the bed roll in feeding the work, means for moving the bed roll between work receiving and work presenting positions with respect to the bladed member, said bed roll being pivotally mounted to yield with respect to the bladed member, and means for mounting the feed roll for bodily movement about two independent axes so that the feed roll may adjust itself about one axis to accommodate variations in the thickness of the work between the feed roll and bed roll and also about another axis to accompany the bed roll in its movements of adjustment to accommodate variations in the thickness of the work between the bed roll and the bladed member. 80
20. In a machine for operating upon hides, skins, leather and other similar pieces of work, a bladed cylinder for operating on the work, a bed roll for co-operation with the cylinder to support the work against the thrust of the cylinder, a feed roll for co-operation with the bed roll in feeding the work past the cylinder, a pair of beams for supporting the feed roll, said beams being mounted for movement about two parallel axes, and swing arms for connecting the bed roll to the beams so that the bed roll and the feed roll may move together with the beams about one axis when the bed roll accommodates itself with respect to the work between it and the cylinder, the feed roll moving with the beams about another axis to yield with respect to the bed roll to accommodate variations in the thickness of the work passing between the two rolls. 85
25. In a machine of the character described, means for operating on a piece of work, a bladed cylinder for operating upon the work, a bed roll for presenting a piece of work to the bladed cylinder, means for yieldingly pressing the bed roll toward the bladed cylinder, a feed roll for co-operation with the bed roll in feeding the work past the bladed cylinder, a pair of beams for supporting the feed roll, means for supporting the beams for pivotal movement about two parallel axes, and means for connecting the bed roll with the beams, the construction and arrangement providing for movement of the feed roll with respect to the bed roll and also movement of the two rolls with respect to the bladed cylinder. 90
30. In a machine for operating upon hides, skins, leather and other similar pieces of work, a bladed member, a bed roll for presenting a piece of work to the bladed member, a feed roll for co-operation with the bed roll in feeding the work, pivoted members for supporting the feed roll for bodily movement about two independent axes, the feed roll being movable about one axis so as to accommodate variations in thickness of work between the feed roll and the bed roll and movable about a second axis to move with the bed roll as the latter moves toward or from the bladed member to accommodate variations in the thickness of the work, means for connecting the bed roll to the pivoted members which support the feed roll, and means for moving the bed roll between work receiving and work presenting positions with respect to the bladed member. 105
35. In a machine for operating upon hides, skins, leather and other similar pieces of work, a work treating cylinder, a bed roll for presenting a piece of work to the work treating cylinder, a feed roll for co-operation with the bed roll in feeding the work past the work treating cylinder, and means for mounting the feed roll for pivotal movement relative to the bed roll and also for movement with the bed roll in directions toward and from the work treating cylinder. 110
40. In a machine for operating upon hides, skins, leather and other similar pieces of work, a bladed member, a bed roll for presenting a piece of work to the bladed member, a feed roll for co-operation with the bed roll in feeding the work, pivoted members for supporting the feed roll for bodily movement about two independent axes, the feed roll being movable about one axis so as to accommodate variations in thickness of work between the feed roll and the bed roll and movable about a second axis to move with the bed roll as the latter moves toward or from the bladed member to accommodate variations in the thickness of the work, means for connecting the bed roll to the pivoted members which support the feed roll, and means for moving the bed roll between work receiving and work presenting positions with respect to the bladed member. 115
45. In a machine for operating upon hides, skins, leather and other similar pieces of work, a work treating cylinder, a bed roll for presenting a piece of work to the work treating cylinder, a feed roll for co-operation with the bed roll in feeding the work past the work treating cylinder, and means for mounting the feed roll for pivotal movement relative to the bed roll and also for movement with the bed roll in directions toward and from the work treating cylinder. 120
50. In a machine for operating upon hides, skins, leather and other similar pieces of work, a bladed member, a bed roll for presenting a piece of work to the bladed member, a feed roll for co-operation with the bed roll in feeding the work, pivoted members for supporting the feed roll for bodily movement about two independent axes, the feed roll being movable about one axis so as to accommodate variations in thickness of work between the feed roll and the bed roll and movable about a second axis to move with the bed roll as the latter moves toward or from the bladed member to accommodate variations in the thickness of the work, means for connecting the bed roll to the pivoted members which support the feed roll, and means for moving the bed roll between work receiving and work presenting positions with respect to the bladed member. 125
55. In a machine for operating upon hides, skins, leather and other similar pieces of work, a bladed member, a bed roll for presenting a piece of work to the bladed member, a feed roll for co-operation with the bed roll in feeding the work, pivoted members for supporting the feed roll for bodily movement about two independent axes, the feed roll being movable about one axis so as to accommodate variations in thickness of work between the feed roll and the bed roll and movable about a second axis to move with the bed roll as the latter moves toward or from the bladed member to accommodate variations in the thickness of the work, means for connecting the bed roll to the pivoted members which support the feed roll, and means for moving the bed roll between work receiving and work presenting positions with respect to the bladed member. 130

17. In a machine for operating upon hides, skins, leather and other similar pieces of work, a bladed member, a bed roll for presenting a piece of work to the bladed member, a feed roll for co-operation with the bed roll in feeding the work, pivoted members for supporting the feed roll for bodily movement about two independent axes, the feed roll being movable about one axis so as to accommodate variations in thickness of work between the feed roll and the bed roll and movable about a second axis to move with the bed roll as the latter moves toward or from the bladed member to accommodate variations in the thickness of the work, supporting arms for connecting the bed roll pivotally with the pivoted members which support the feed roll, and a toggle mechanism for moving the bed roll between work receiving and work presenting positions with respect to the bladed member.

18. In a machine for operating upon hides, skins, leather and other similar pieces of work, a work treating cylinder, a bed roll for presenting the work to the work treating cylinder, means for feeding the work progressively past the cylinder, a work support for co-operation with the bed roll in supporting the work for the operation of the work treating cylinder, means for pressing the work support independently of the bed roll in a direction toward the work treating cylinder, means for causing relative movement between the bed roll and the work supporting member on one side and the work treating cylinder on the other so that pieces of work may be readily introduced and subsequently acted upon, and means manually operable while the machine is in operation for adjusting the pressure of the work support with respect to the cylinder.

19. In a machine for operating upon hides, skins, leather and other similar pieces of work, a rotary cylinder for treating the work, a bed roll for presenting the work to the rotary cylinder, means for feeding the work, a work support for co-operation with the bed roll in presenting the work to the work treating cylinder, means for connecting the work support to the bed roll to move therewith, means for yieldingly pressing the bed roll in a direction toward the work treating cylinder, means independent of the last-mentioned means for yieldingly pressing the work support in a direction toward the cylinder, so that both the bed roll and the work support may yield independently to accommodate themselves to variations in the thickness of the work passing between them and the work treating cylinder, and means manually operable while the machine is in operation for adjusting instantaneously the pressure of the work support with respect to the cylinder.

20. In a machine for operating upon hides,

skins, leather and other similar pieces of work, a work treating cylinder, a bed roll for supporting a piece of work against the thrust of the cylinder, means for mounting the bed roll so that it may move yieldingly away from the cylinder, a feed roll for co-operation with the bed roll in feeding the work, a work support for co-operation with the bed roll in pressing the work against the cylinder and mounted to move with the bed roll, and pivoted members for supporting the feed roll for bodily movement with respect to the bed roll and also for bodily movement with the bed roll and the work support in movements of the latter toward and from the work treating cylinder in accommodating variations in the thickness of the work passing between them and the cylinder.

21. In a machine for operating upon hides, skins, leather and similar pieces of work, a bladed member, a bed roll for supporting a piece of work against the thrust of the bladed member, means for mounting the bed roll so that it may move yieldingly away from the bladed member, a feed roll for co-operation with the bed roll in feeding the work, an auxiliary work supporting member for co-operating with the bed roll in pressing the work against the bladed member and mounted to move with the bed roll, pivoted members for supporting the feed roll for bodily movement about two axes, about one axis for permitting yielding of the feed roll with respect to the bed roll, and about the other axis to permit movement of the feed roll with the bed roll and auxiliary work support as the latter two adjust themselves with respect to the bladed member, means connected to the pivoted members for yieldingly pressing the bed roll toward the bladed member, and other means for yieldingly pressing the work support in a direction toward the bladed member.

22. In a machine for operating upon hides, skins, leather and other similar pieces of work, a bladed member, a bed roll for presenting a piece of work to the bladed member, a feed roll for co-operation with the bed roll in feeding the work, a work support for co-operation with the bed roll in presenting the work to the bladed member, means for supporting the work support upon the bed roll so that it may move with the latter, pivoted members for supporting the feed roll, said pivoted members being pivotally supported for movement about two independent axes, about one axis for bodily movement of the feed roll with respect to the bed roll and about the other axis for movement of the feed roll with the bed roll and work support during movements of the latter to accommodate variations in thickness of the work passing over the bladed member, and toggle mechanism for moving the bed roll and the work support between work receiving and

- work presenting positions with respect to the bladed member.
23. In a machine for operating upon hides, skins, leather and other similar pieces of work, a bladed member, a bed roll for presenting a piece of work to the bladed member, a feed roll for co-operation with the bed roll in feeding the work, pivoted members for supporting the feed roll, pivoted bell 5 crank levers for pivotally mounting the first-mentioned pivoted members at one end of each of said pivoted members, and means for yieldingly operating upon the other ends of the pivoted members for yieldingly resisting 10 a separating movement between the feed roll and the bed roll, spring means for yieldingly resisting movement of the bell crank levers in one direction, arms for connecting the bed roll to the pivoted members, and means for 15 moving the bed roll between work receiving and work presenting positions with respect to the bladed member and the feed roll.
24. In a machine for operating upon hides, skins, leather and other similar pieces of work, a bladed member, a bed roll for presenting the work to the bladed member, a feed roll for co-operation with the bed roll in feeding the work past the bladed member, and a work support for co-operation with the 20 bed roll in presenting the work to the bladed member, said work support comprising a plurality of yieldingly mounted presser members having surfaces contacting with each other in side-by-side relationship, said presser members being so constructed that arranged with respect to each other that the contacting surfaces extend at an angle other than a right angle to the direction of feed of the work.
25. In a machine for operating upon hides, skins, leather and other similar pieces of work, a work treating cylinder, a bed roll for presenting a piece of work to the cylinder, a feed roll for co-operation with the bed roll in feeding the work, a work support for co-operation with the bed roll in supporting the work for the operation of the cylinder, means for pivoting the work support to move with the bed roll, means for pressing the 30 work support yieldingly toward the cylinder, means for moving the bed roll and the work support between work receiving and work presenting positions with respect to the cylinder, and manually operable means for 35 instantaneously adjusting the pressure of the work support with respect to the cylinder while the machine is in operation.
26. In a machine for operating upon hides, skins, leather and other similar pieces of work, a bladed member, a bed roll for presenting a piece of work to the bladed member, a feed roll for co-operation with the bed roll in feeding the work, an auxiliary work support for co-operation with the bed roll in presenting the work to the bladed member, means 40 for connecting the work support directly to the bed roll to move therewith, means for yieldingly pressing the bed roll in a direction toward the bladed member, means for yieldingly pressing the work support in a direction toward the bladed member so that both the bed roll and the auxiliary support may yield to accommodate themselves to variations in the thickness of the work passing between them and the bladed member, and a 45 manually operable eccentric for adjusting instantaneously the pressure of the work support with respect to the bladed member.
27. In a machine for operating upon hides, skins, leather and other similar pieces of work, a rotary member for treating the work, a bed roll for presenting the work to the rotary member, a feed roll for co-operation with the bed roll in effecting rolling of the work and in feeding the work past the rotary member, means for moving the bed roll between work receiving and work presenting positions with respect to the rotary member, means located in the angle formed by the feed roll, the bed roll and the work treating 50 member, for spraying liquid upon the piece of work passing between the bed roll and the work treating member, and means controlled by movements of the bed roll between work receiving and work presenting positions, for 55 causing operation of the spraying means while the bed roll is in work presenting position and for rendering the spraying means inoperative while the bed roll is in work receiving position.
28. In a machine for operating upon hides, skins, leather and other similar pieces of work, a bladed member, a bed roll for presenting a piece of work to the bladed member, a feed roll for co-operation with the bed roll in feeding the work past the bladed member, means for moving the bed roll between work receiving and work presenting positions with respect to the bladed member, a perforated 60 pipe for spraying liquid upon the piece of work passing over the bed roll, a valve in the pipe, and means comprising an adjustable tappet connected to move with the bed roll for controlling the valve so that liquid is sprayed upon the work while the bed roll is in work presenting position, and so that spraying of the liquid ceases while the bed roll is in work receiving position.
29. In a machine for operating upon hides, skins, leather and other similar pieces of work, a bladed member, a bed roll for presenting a piece of work to the bladed member, a feed roll for co-operation with the bed roll in feeding the work past the bladed member, means for moving the bed roll between work receiving and work presenting positions with respect to the bladed member, a perforated pipe for spraying liquid upon the work passing over the bed roll, a valve in the pipe, and a tappet carried by the bed roll moving means

and arranged to cause the valve to be opened and closed automatically in accordance with the movements of the bed roll between work receiving and presenting positions.

- 5 30. In a machine for operating upon hides, skins, leather and other similar pieces of work, a bladed member, a bed roll for presenting a piece of work to the bladed member, a feed roll for co-operation with the bed roll
10 in feeding the work past the bladed member, means for moving the bed roll between work receiving and work presenting positions with respect to the bladed member, a perforated pipe for spraying liquid upon work passing
15 over the bed roll, a valve in the pipe, a piston extending exteriorly of the valve, and an adjustable tappet connected to move with the bed roll for controlling the piston so that upon movement of the bed roll to work presenting position the valve is operated to cause spraying of the liquid upon the work, the piston moving to closing position upon movement of the bed roll away from work presenting position.
- 20 31. In a machine for operating upon hides, skins, leather and other similar pieces of work, a bladed member, a work support for presenting a piece of work to the bladed member, power means for moving the work
25 support to present the work to the bladed member, a clutch for controlling the power means, a shaft and a starting treadle for controlling the clutch, said treadle being freely mounted on the shaft so that after depression thereof for throwing in the clutch it can be returned to its initial position of rest independently of the return movement of the clutch parts, and means for returning the treadle to initial position upon its being released by the operator.
- 30 32. In a machine for operating upon hides, skins, leather and other similar pieces of work, a work treating cylinder, a work support for presenting a piece of work to the cylinder, power means for moving the work support to present the work to the cylinder, a clutch for controlling the power means, means for automatically throwing the clutch out of action at each half cycle, a shaft, a
35 starting treadle for operating the shaft to control the clutch, said treadle being freely mounted on the shaft, and yielding means operative to return the treadle to its initial position of rest irrespective of the movements of the shaft and clutch parts.
- 40 45 50 55

In testimony whereof I have signed my name to this specification.

GUSTAV ADOLF SCHETTLER.
